UNITED STATES PATENT OFFICE.

LAURENCE PONET, OF NEW YORK, N. Y.

ROUND EXTENSION-TABLE.

No. 894,049.

Specification of Letters Patent.

Patented July 21, 1908.

Application filed October 17, 1907. Serial No. 397,767.

To all whom it may concern:

Be it known that I, LAURENCE PONET, a subject of the King of Belgium, and a resident of the city of New York, borough of 5 Manhattan, in the county and State of New York, have invented a new and Improved Round Extension-Table, of which the following is a full, clear, and exact description.

The invention relates to furniture and its 10 object is to provide a new and improved round extension table, having a top formed of a fixed center-piece, and segmental sections, capable of being folded under the fixed center or extended flush with the latter, to 15 increase the size of the table top.

The invention consists of novel features and parts and combinations of the same, which will be more fully described herein-after and then pointed out in the claims.

20 A practical embodiment of the invention is represented in the accompanying drawings forming a part of this specification, in which similar characters of reference indicate corresponding parts in all the views.

25 Figure 1 is an inverted plan view of the improvement, showing the table-top extended; Fig. 2 is a sectional side elevation of the same on the line 2—2 of Fig. 1; Fig. 3 is an inverted plan view of the improvements showing the segmental top sections folded under the center-piece of the table top; Fig. 4 is a 30 sectional side elevation of the same on the line 4—4 of Fig. 3, and Fig. 5 is a similar view of the same on the line 5—5 of Fig. 3.

35 The top of the table consists of a rounded center-piece A and segmental sections B, capable of being either folded beneath the center-piece A when a small round table is desired (see Figs. 3, 4 and 5), or extended flush with

40 the center-piece A, to form an enlarged round table, as illustrated in Figs. 1 and 2. The center-piece A is mounted on the usual frame C, and legs D, adapted to rest on the floor. Each of the segmental sections B, of

45 which there are preferably four, is formed of a middle piece B', and end pieces B², B³ connected by hinges E to the middle piece B' to fold upon the under side thereof, and each end piece B² is provided at its under side 50 with a flange B⁴ for the adjacent end piece B³ of the next section B to rest on.

The middle pieces B' of the several sections B are connected by hinges F with the under side of the center-piece A, to permit 55 of swinging the middle pieces B' down under the center-piece A within the frame C, as

plainly indicated in Figs. 3, 4 and 5. In order to hold the middle pieces B' of the segmental sections B in an extended position, supports G are provided in the 60 form of slides, mounted to slide in bearings H attached to the under side of the center-piece A, and each sliding support G is provided near its outer end with a depending knob G', adapted to be taken hold of by the 65 operator for drawing the support out into active position, as shown in Figs 1 and 2, or pushing the sliding support inward out of engagement with the middle pieces B', as indicated in Figs. 3, 4 and 5. The end 70 pieces B² and B³ of adjacent sections B are supported in an extended position by a bracket I, connected by a hinge J with the corresponding table leg D, the said bracket I when extended or swung outward forming 75 a support for the flange B⁴ previously mentioned, and which is secured to one of the end pieces B² and supports the adjacent end piece B³. Now when the segmental sections B are extended, as shown 80 in Figs. 1 and 2, they are supported by the sliding supports G and the hinged brackets I, to form a round table, and when it is desired to form a smaller round table of the size of the center-piece A, then the slides G 85 are pushed inward and the brackets I are swung inward into the positions shown in Figs. 3, 4 and 5, to permit of holding the end pieces B², B³ onto the under side of the middle pieces B', and to allow of swinging 90 the end pieces B' inward into the space confined by the frame C, so that the segmental sections B when in this folded position are completely out of the way of the knees of the persons seated at the small round table. 95

In order to lock the folded segmental sections B in position, suitable devices may be provided, such, for instance, as cleats K, pivoted on a post L, arranged centrally on the under side of the center A, the said cleats 100 K engaging two diametrically disposed segmental sections B, while the other two diametrically-disposed sections B are engaged and locked in place by hooks N, likewise attached to the post L. It is understood that the oppositely disposed segmental sections locked in place by the cleats K are first folded inward and locked in place by the cleats (see Figs. 3 and 4), after which the other two sections B are folded inward 105 on top of the previously folded sections B and then locked in place by the hooks N,

as will be readily understood by reference to Figs. 3 and 5. The hinges F for the several middle pieces B' are made of as many joints as are required to allow the folding of the 5 middle pieces within the frame C, as above described and illustrated in Figs. 3, 4 and 5.

When it is desired to extend the table, the sections B held locked by the hooks N are first unlocked and swung outward, flush with 10 the center-piece A, and then locked in this position by pulling the corresponding slides G outward. When this has been done, the other two sections B are unlocked by the cleats K and swung outward, flush with the 15 center-piece A, and locked in this position by pulling the corresponding sliding supports G outward. The end pieces B², B³ are then extended to complete the round table extension, and the brackets J are then 20 swung outward, to support the said end pieces, as previously explained.

The round extension table shown and described is very serviceable for use in hotels, restaurants and the like, as it permits increasing 25 the size of the table for seating the desired number of persons at the table, and without disturbing the decorations on the table and held on the center-piece A.

Having thus described my invention, I 30 claim as new and desire to secure by Letters Patent:

1. A round extension table, consisting of a square frame, legs at the corners of the frame, a round center piece on the frame, segmental 35 sections, each formed of a middle piece and end pieces hinged to the middle piece to fold upon the same, one end piece of each section being provided with a projection upon which the adjacent end piece rests, a plurality of 40 hinges connecting the middle piece of each section with the under side of the center piece, whereby the sections can fold inside of the frame, slides on the under side of the center piece for supporting the middle pieces 45 of the sections, brackets hinged to the legs for supporting the end pieces of adjacent sections, cleats pivoted to the center piece for holding two of the middle pieces of the sections folded, and hooks carried by the 50 center piece for engaging the other two middle pieces of the sections to hold them folded upon the first-named sections.

2. A round extension table, comprising a

rectangular frame, legs at the corners of the frame, a round center piece on the frame, 55 segmental sections, each formed of a middle piece and end pieces hinged to the middle piece to fold upon the same, one end piece of each section having a flange upon which the adjacent end piece rests, a plurality of 60 hinges connecting the middle piece of each section with the under side of the center piece, whereby the sections can fold inside of the frame, slides on the under side of the center piece for supporting the middle pieces 65 of the sections, brackets hinged to the legs for supporting the end pieces of adjacent sections, and means for holding the sections folded inside of the frame.

3. A round extension table, comprising a 70 rectangular frame, legs carried by the frame, a round center piece on the frame, segmental sections, each formed of a middle piece and end pieces hinged to the middle piece, a plurality of 75 hinges connecting the middle piece of each section with the under side of the center piece, whereby the sections can fold inside of the frame, means for holding the sections extended, cleats pivoted to the center piece for holding two of the sections 80 folded, and hooks carried by the center piece for engaging the other two sections to hold them folded.

4. A round extension table, comprising a 85 rectangular frame, legs carried by the frame, a round center piece on the frame, segmental sections, each formed of a middle piece and end pieces hinged to the middle piece to fold upon the same, a plurality of hinges for connecting the middle piece of each section with 90 the under side of the center piece, the number of hinges for two opposing sections being greater than for the other two sections, whereby the sections can be folded inside of the frame with two of the sections on the 95 other two sections, means for holding the sections folded, and means for holding the sections extended.

In testimony whereof I have signed my name to this specification in the presence of 100 two subscribing witnesses.

LAURENCE PONET.
